UNITED STATES PATENT OFFICE

2,486,951

COMBINATION SHADE AND CURTAIN
BRACKET

Luther P. Jeffreys, Fort Worth, Tex.

Application November 25, 1946, Serial No. 712,220

1 Claim. (Cl. 248—253)

1

This invention relates to devices for supporting window shades, curtains and draperies, and it has particular reference to right- and left-hand mounting brackets formed with appurtenances for attaching shade rollers and curtain or drape rods, such as that illustrated and described in a co-pending application filed by Luther P. Jeffreys on September 7, 1946, and bearing Serial No. 695,377, and its principal object resides in the provision of a single unit capable of being stamped or formed from a light gauge metal or plastic in a compact structure which is both attractive and practical.

Another object of the invention is that of providing an economical unit having integral projections formed to accommodate the securing ends of conventional curtain rods arranged in pairs, both of which may be identical in length and form, and thereby afford an arrangement which obviates the necessity for utilizing paired rods of different dimensions as well as the requirement for merchants to stock a variety of types and sizes of curtain rods.

It is broadly contemplated that the invention include, in a single unit, a combination of integral elements compactly arranged so that it can be economically produced by stamping and forming processes and requiring a minimum of material.

While the foregoing objects are paramount, other and lesser objects will become manifest as the description proceeds, taken in connection with the appended drawings wherein:

Figure 1 is a perspective illustration showing a pair of brackets embodying the invention operatively secured to a window header, a window shade and a pair of curtain rods being fragmentarily shown attached to one of said brackets.

Figure 2 is an end elevational view of one of said brackets showing a shade roller support.

Figure 3 illustrates the invention in vertical section taken on lines 3—3 of Figure 5.

Figure 4 is an opposite end elevational view of the invention shown in Figure 2.

Figure 5 illustrates the invention in plan.

Figure 6 is a lateral cross-sectional view of a modified form of the invention, taken on lines 6—6 of Figure 7, and

Figure 7 is a fragmentary elevational view of one of the rod supports of the modified form of the invention.

The invention, therefore, comprises an integral unit formed with a base portion 10 which defines a tab 11 on each side affording means for attaching the same to a window header 12, in the manner shown in Figure 1. It is contemplated that the bracket be formed from a single strip of material, such as aluminum, or other suitable metal or plastic, and folded to define spaced projecting elements arranged in parallel relationship and extending at right angles from the base member 10.

2

A shade roller 13 is operatively supported at each end in projecting brackets 14 and 15, the former being conventionally formed with a notch 16 to receive the tensioned shaft on one end of the roller 13, while the latter bracket 15 has an aperture 17 through which the spindle 18 of the roller 13 is operatively arranged, as shown in Figure 1.

The rod brackets 19 and 20 are spaced apart and from the roller brackets 14 and 15 and shaped to conformably receive the ends 21 of curtain rods 22 which may be identical in form and dimensions, as illustrated in Figure 1, the outer members 19 being longer than their companion members 20 to space the longitudinal portions 23 of the rods 22 when the same are attached.

The brackets 19 are formed with a depending portion 24 which defines a shoulder α providing a stop for the end of the outer rod and spacing the same from the base 10, as shown in Figure 1, and properly separating the longitudinal portions 23, of the rods 22, the ends 21 of the inner rod being fixed upon the shorter bracket 20 and may be urged against the base 10. It is therefore desirable that the distance between the stops α and the ends of the rod brackets 19 be equal to the entire length of the shorter brackets 20.

Each of the rod brackets 19 and 20 are formed with a boss b , in the preferred form of the invention, to frictionally engage the inner surfaces of the rods 22 and firmly secure the same against displacement. A modification of this arrangement is illustrated in Figures 6 and 7 in the form of a cut-out tab c crimped outwardly to provide a tensioning engagement with the rods.

Manifestly, the structure herein shown and described is capable of certain changes and modifications, by persons skilled in the art, without departing from the spirit and intent of the invention or the scope of the appended claim.

What is claimed is:

In a shade and curtain bracket, integral right- and left-hand units capable of being stamped from sheet metal, a base portion, a shade supporting member and a pair of rod supporting projections formed parallel on each unit by folding and pressing said metal in a series of spaced folds extending laterally from said base portion, one of said projections extending outwardly beyond its companion, and means formed in each of said projections frictionally retaining said rods thereon.

LUTHER P. JEFFREYS.
